STEAM INJECTOR

Walter H. Tinker, Boston, Mass., assignor of
fifty-one one-hundredths to Edward J. Mallon,
Chillicothe, Ohio

Application February 17, 1942, Serial No. 431,313

9 Claims. (Cl. 103—265)

This invention relates to improvements in steam injectors. The general object of the invention is to provide a simple and reliable feed water heating injector having relatively few parts, and particularly adapted for steam locomotive service.

It is within the general purview of the invention to provide an injector having a thermal efficiency, commensurate with its capital cost and maintaining an average high temperature of the delivery water which tends to improve locomotive efficiency, and to provide a device somewhat automatic in its rate of delivery and of the water heating type, controlled by a single lever from the cab on the locomotive.

One of the more specific objects of the invention is to provide a steam injector wherein the starting, cutting off and water delivery regulation are accomplished by the manipulation of a single lever or rod which actuates linkage so connected to the live steam valve and water valve as to operate these valves simultaneously through ranges of movement of different amplitude, the water valve moving at the faster rate, said valves and the conduits which they control being so correlated that both valves reach their full delivery capacity early in their respective ranges of opening movement and at about the same time, the water valve and/or its conduit being so constructed as to produce a throttling region within that part of the range of movement of said water valve beyond the point at which full capacity delivery is first attained, ineffective when the valves are opened quickly as at starting, but serving as a datum for water volume varying movements of said water valve beyond said throttling region when said valves are moved slowly, the corresponding movement of said live steam valve taking place within the full delivery capacity phase of the range of movement of said live steam valve, variations in water delivery being accomplished without corresponding variations in the live steam jet. This means that the live steam valve always opens sufficiently to pass an amount of steam commensurate with the amount of water to be pumped.

Another object of the invention is the provision of an injector of the type described, in which provision is made for the admission of exhaust steam, when available, to the water inlet chamber of the injector for imparting its modicum of heat to the water, said exhaust steam being admitted past the check valve which opens under the pressure of the exhaust steam and which valve is locked closed when said injector is cut off.

A further object of the invention is the provision of a velocity and pressure building venturi in the water inlet chamber confronting the exhaust steam nozzle and discharging in the region of the live steam entraining nozzle of the injector, whereby the exhaust steam builds up some pressure in the water which it delivers to the main venturi of the injector, this venturi having no spillways nor openings communicating with the atmosphere.

Still another object of the invention is to provide means for holding the overflow valve closed under conditions in which the injector is operating with some back pressure in the overflow chamber.

Other objects of the invention will appear as the following description of a preferred and practical embodiment thereof proceeds.

In the drawings which accompany and form a part of the following specification, and throughout the several figures of which the same characters of reference have been employed to designate identical parts:

Figure 1 is a vertical section through an injector embodying the principles of the present invention;

Figure 2 is an axial section through the exhaust steam check valve;

Figure 3 is a similar view through the water valve and appurtenant mechanism;

Figure 4 is a cross-section taken along the line 4—4 of Figure 3;

Figure 5 is a longitudinal axial section through the live steam valve taken at right angles to Figure 1;

Figure 6 is a cross-section taken along the line 6—6 of Figure 1;

Figure 7 is a cross-section taken along the line 7—7 of Figure 1; and

Figure 8 is a longitudinal axial view showing a modification involving the water valve and the conduit controlled thereby.

Referring now in detail to the several figures, and first referring to Figure 1 which shows the general layout of the injector, it comprises a casing 1 adapted to be suitably secured to the side of locomotive structure by means such as the bolts 2 which pass through the perforated lugs 3. The casing 1 has an axial bore 4 extending longitudinally therethrough having a removable cap 5 closing its lower end. At its upper end it has the lateral port 6, (see also Figure 5), with which the live steam conduit 7 communicates, said conduit taking live steam from the boiler. Below the live steam port 6 the casing 1 is provided to

one side with a steam and water overflow outlet 8 controlled by the overflow valve 9. At the other side, the casing 1 is provided with the threaded spigot 10, to which is screwed a fitting 11. This fitting has a water inlet port 12 suitably connected to a water tank or other source of water supply. At its end the fitting 11 has the threaded spigot 13 adapted to be connected by a suitable conduit with the exhaust steam from the cylinder of the locomotive. The casing 1 is also provided with the threaded spigot 14 adapted to be connected to the boiler at the point to which the make-up water is to be supplied.

The details of the casing, as above described, are matters of design and may be varied in any manner desired, without transcending the scope of the invention.

A live steam nozzle which as a whole is designated by the reference character 15, communicates with the live steam port 6. This comprises a cup-shaped valve chamber 16 having a threaded annular base screwing into a restriction 17 within the casing 1. A central live steam Venturi nozzle 18 is mounted in the lower end of the valve chamber 16 communicating at its lower end with a velocity and pressure building venturi 19. This venturi is made up of several parts 20, 21 and 22, provided with the lateral spillways 23, 24 and 25 which communicate with the overflow water chamber 26 within the casing 1 and the outlet to which chamber is controlled by the overflow valve 9.

The details of construction of this venturi are not critical to the invention, but may be described as follows. The connected parts 20 and 21 have a downwardly convergent or velocity building bore 27, while the part 22 has the downwardly divergent or pressure building bore 28 opening into the pressure water chamber 29, which is in communication with the delivery water spigot 14. The pressure building part 22 is not only connected to the part 21 by the threaded connection 30, but is also connected to the casing 1 by the threaded connection 31 separating the pressure water chamber 29 from the overflow chamber 26. The spillways 23 and 24, as shown, are in direct communication with the overflow chamber 26, while the spillway 25 is in indirect communication with the overflow chamber through the passages 32, which are best shown in Figure 7.

The fitting 11 defines an inlet water chamber 33 which is in valve communication with the water inlet port 12 by means of the water valve 34. The inlet water chamber 33 communicates with a water entraining chamber 35 in the casing 1 which surrounds the live steam nozzle 18. The entraining chamber 35 is separated from the overflow chamber 26 by the upper end of the injector venturi 19, which is screwed to the wall of the bore 4 by the threaded connection 36. Water from the entraining chamber 35 enters the venturi 19 through the annular passage 31.

The injector is provided with a live steam entraining nozzle 38 which opens into the entraining chamber 35 confronting the annular passage 37. Both the live steam forcing nozzle 18 and the live steam water entraining nozzle 38 are in valve control by means of the live steam valve which as a whole is designated by the reference character 39.

The live steam valve comprises a cup-shaped valve member 40, operating in the valve chamber 16, that side of the valve chamber which confronts the live steam port 6 being open, as

shown at 40 in Figure 5, said valve chamber being normally closed with respect to the live steam forcing and entraining nozzle when the cup-shaped member is on its seat, but in communication with said nozzles when the cup-shaped member 40 is lifted from its seat.

A ring nut 41 screws into the upper end of the cup-shaped member 40 and imprisons the head 42 of the operating rod 43, with some lost motion, so that the operating rod may rise a small distance without lifting the live steam valve. The head 42 when seated, as shown in Figure 1, makes a steam tight fit with the cup-shaped member 40 against which it rests.

The water valve comprises a head member 44 which normally rests upon a seat 45 between the inlet port 12 and the water inlet chamber 33. A ring nut 46 screws into the top of the head member 44, imprisoning the enlarged end 47 of a stem 48 which operates the water valve. There is some lost motion between the enlarged end 47 and the ring nut, so that the stem 48 can rise a small distance before the water valve is lifted.

Both the rod 43 and the stem 48 are packed against leakage by the glands 49 and 50, respectively.

The rod 43 and the stem 48 are each pivotally connected at the points 51 and 52 to a link 53 pivoted laterally of both said rod and said stem at the point 54 so that when said lever 53 is swung about its pivotal connection 54, said rod and said stem are raised but at an unequal rate, the stem 48 being lifted at a faster rate than the rod 43 and therefore having a longer range of movement. Inasmuch as the pivotal connections 51 and 52 move in arcs and it is desired to avoid lateral pressures upon the respective rod 43 and stem 48, the lever 53 is pivotally connected to a swinging link 55 pivotally mounted as at 56 upon the casing of the injector. The injector is operated by a rod or lever 57 pivotally connected to the lever 53 and which is pulled upward to open the valves 39 and 34.

Both the live steam valve 39 and the water valve 34 and the conduits which they control are so constructed and designed that they open to their full respective steam admitting and water admitting capacity at an early period in their range of opening movements.

Before an injector is started, the overflow chamber 26 contains water which also at least partially fills the venturi of the injector. If the injector were started with live steam alone, this water would be blown out of the venturi and the overflow chamber through the valve 9, the latter opening against steam pressure, and the venturi would be filled solely with steam and would deliver no water to the boiler. It is therefore quite essential that water must be entrained with the steam jet as the latter enters the venturi. Therefore, both the live steam and water valves must be simultaneously opened. Inasmuch as the live steam enters under pressure, it is essential that both the steam and water valves reach their full capacity almost as soon as they are opened, and that the water valve open faster than the steam valve. In the operation of any injector it is therefore customary to manipulate the starting lever by a quick jerk or by a rapid movement through a time interval of not more than a second or two. In the subject injector, starting is accomplished by pulling upwardly upon the lever 57 by a quick movement, opening both the live steam valve 39 and the water valve 34 through

their entire range of movement in an opening direction. As has been stated, both valves reach their full open capacity at an early point in their respective ranges of opening movement. In order for the live steam to acquire velocity in the convergent portion of the venturi 19, it must displace the inert water in said venturi, which it does by forcing it through the spillways 23, 24 and 25 into the overflow chamber, at the same time carrying with it the entrained water which will be built up in the divergent portion of the venturi to sufficient pressure to enter the boiler. The water and steam forced out through the spillways 23, 24 and 25 opens the valve 9 and overflows through the port 8. Normally, an injector operates under slightly less than atmospheric pressure, so that as soon as the injector is operating, the overflow valve 9 automatically closes under the reduced pressure within the overflow chamber 26.

At this time a maximum volume of water is being admitted by way of the water inlet port 12 and the maximum amount is being delivered to the boiler. It is, however, desirable to regulate the amount of water delivered to the boiler, and this should be done without diminishing the force of the live steam jet beyond that required for the work done. Since the live steam valve 34 reaches its full capacity opening at an early stage in its range of opening movement, and continues to have this maximum capacity during the rest of its range of opening movement, the present invention takes advantage of this condition by performing the water volume varying movements of the water valve in that part of the range of opening movement of the water valve which corresponds to the full capacity range of movement of the live steam valve or adjusted so that the live steam valve admits sufficient live steam for the amount of work performed.

In order to do this, the water valve 34 includes a throttling disk 58 of such size as just to freely pass through the opening in the valve seat 45. This disk is secured axially of the valve head 44 on a stem 59 which extends beneath said valve head. When the valve head 44 is lifted from its seat so that the opening between said valve head and seat is equal to the opening between the disk 58 and said seat, the water valve is open to full capacity. When the lever 53 is swiftly lifted in starting the injector, the disk 58 passes from the lower side of the seat 45 to the upper side so fast that it has no throttling effect upon the injector, inasmuch as the capacity of the inlet water chamber 33 is sufficient to meet the demands of the injector during the moment in which the disk 58 is in transit through the plane of the seat 45, and when the water valve 34 is at the extreme upper limit of its range of opening movement the disk 58 is above the seat 45 a sufficient distance to give the water valve its full open capacity. Thus in starting, the disk 58 has no throttling effect.

Now, in regulating the volume of water, the lever 53 is very slowly swung upwardly or downwardly by manipulation of the lever 57, the disk 58 being always above the plane of the seat 45, being brought close to said seat to reduce the volume of water delivered, or raised with respect to said seat to increase the volume delivered. The live steam valve, of course, follows the movements of the water valve, but always in that part of the range of movement of the live steam valve which represents the full open capacity of said valve for the amount of water handled, the

amount of steam valve opening being adjusted in extent by the design but the downward movement of the steam and water valves effectually reducing the water passage area but not decreasing the steam valve area beyond any predetermined point necessary for adequate steam to water ratio. In cutting off the injector the lever 53 is moved all the way down to seat both the live steam and the water valves in the positions shown in Figure 1. Thus, by the manipulation of a single lever, both starting and cutting off of the injector, as well as regulation of the volume of water delivered to the boiler is accomplished in a simple and efficient manner.

Reference may now be had to Figure 8 which shows a modified form of the invention as regards the water valve which amounts to substantially a reversal of parts. In this form of the invention the head 60 of the water valve is not provided with a disk, but instead, an annular throttling rib 61 is provided on the inside of the valve chamber above the valve seat 62 and suitably spaced therefrom. When the valve 60 is lifted to a position half way between the seat 62 and rib 61 it is in a position of full open capacity. When it has been lifted to the upper limit of its range of movement, it is still in a position of full open capacity. If the transition is made quickly from its full open position below the rib 61 to its full open position above the rib 61, the throttling effect upon the injector is nil, and the inlet water chamber 33 is of sufficient capacity to supply for an instant the demands of the injector. When it is desired to regulate the volume of water delivered, this is done while the valve head 60 is above the rib 61. It is slowly made to approach said rib for reducing the volume delivered, and slowly raised while above said rib for increasing the delivered volume. During these volume regulating movements of the water valve, the live steam valve is making corresponding movements but of less amplitude, and which movements are confined to that part of the range of said live steam valve in which it is adequately open.

Returning now to Figure 1, in order to adjust the time point at which steam enters the forcing nozzle 18 with respect to the time at which the water valve 34 begins to open, the live steam valve 39 is provided with an extension 63 normally entering the upper end of the forcing nozzle 18 when the live steam valve is closed, and substantially occluding said live steam valve. When the live steam valve is raised, it opens to the entraining nozzle a moment prior to its communication with the bore of the forcing nozzle. This interval can be varied by backing out the ring nut 41, more or less screwing it down against interposed shims (not shown). This varies the lost motion between the head 42 and the ring nut, and permits the extension 63 to be drawn up a greater or less distance with respect to the inlet end of the forcing nozzle 18 before the valve 39 raises from its seat.

The exhaust steam from the cylinders of the locomotive, when present, is employed to impart its quota of heat to the water, and to correspondingly increase the efficiency of the locomotive operation. The exhaust steam enters the injector through a conduit connected to the spigot 13, and passes through the adjacent portion 64 of an exhaust steam nozzle 65, the bore of which is intersected by the gate valve 66. Said gate valve when in its lowermost position, as shown, closes the bore through the exhaust steam nozzle. It

has a port 67 which registers with the bore in the exhaust steam nozzle when the gate valve is in elevated position. The gate valve is connected at the lower end of the valve rod 68 provided with a head 69 retained within a recess in the gate valve, with some lost motion between said valve and stem. The lower part of the gate valve 66 is received in a chamber 70 formed in the fitting 11.

Above the exhaust steam nozzle 65, the fitting 11 is formed as a cylinder 71, in which a plunger 72 operates, the valve rod 68 being secured to said plunger and extending therebeyond, through an aperture in the top of said cylinder and terminating beneath the lever 53. The valve rod 68 makes a loose fit where it passes through the top of the cylinder, permitting atmospheric leakage into the cylinder chamber above the plunger so that the latter can descend gravitationally when not sustained by exhaust steam pressure. When the lever 53 is in the closed position with respect to the live steam and water valves, it contacts the top of the valve rod 68 and locks the gate valve shut.

There is a port 73 provided between the exhaust steam supply chamber and the cylinder chamber 74 beneath the plunger, so that when exhaust steam reaches the closed gate valve it simultaneously acts upon the plunger via port 73, lifting it, so as to open the gate valve. The forward end of the exhaust steam nozzle confronts the convergent end of a venturi 75, which venturi forms a conduit for the water and exhaust steam delivering the water to the entraining chamber 35 of the venturi 19. The forward end of the exhaust steam nozzle is of smaller diameter than the adjacent end of the venturi 75 defining an annular space 76 in the inlet water chamber 33 through which water is entrained into the venturi 75 by the jet of exhaust steam issuing from the exhaust steam nozzle. The venturi 75 has a pressure building portion 78 opening adjacent the entraining passage 37 of the main venturi. Thus, some water pressure is built up by the exhaust steam in the region of its induction into the main venturi. The water is heated by the exhaust steam.

The chamber 70 formed in part 11, which chamber 70 extends all the way around nozzles 64 and 65, contains a pressure very nearly equal to that at the throat gap between nozzles 64 and 65 and the leakage steam around valve rod 68 from chamber 74 is absorbed by nozzle 65. When valve 66 is closed (in farthest downward position shown in Figure 1) it acts as a non-return valve in either direction of attempted flow through the nozzle parts 64 and 65.

Inasmuch as there are occasions in which the injector operates with the overflow chamber 26 under a pressure somewhat greater than atmospheric pressure, means are provided for holding the overflow valve 9 closed during such operation. Figure 1 shows that the valve 9 is provided with a stem 78 which telescopes within a closed topped plunger 79 slideable within a tubular guide 80 formed on the inner side of a removable cap 81 which closes an aperture in the casing 1 above the valve 9. The tubular guide is in turn closed by a cap 82 connected by a tube 83 to a source of steam supply, said tube having a valve 84 by means of which the steam may be cut on or off. Ordinarily, the cushion of air within the plunger chamber 85 is sufficiently compressible to permit the valve 9 to lift under the overflow pressure in the overflow chamber 26. When it is de-

sired to positively hold the valve 9 closed, steam is turned into the plunger chamber 85, depressing the plunger, the top of which abuts against the valve stem and holds the valve down to its seat.

When there is no exhaust steam present, the exhaust steam valve 66 remains closed by gravity, and the injector operates solely through the agency of the live steam.

It is obvious to those skilled in the art that my improved injector, as disclosed, simplifies the operation by providing that not only starting and cutting off of the injector, but regulation of the volume of water delivered to the boiler may be readily accomplished by the manipulation of a single handle or lever, moving it quickly throughout its entire range of movement for starting, and then moving it slowly within the upper part of its range of movement for varying the water supply to the injector without varying the steam supplied thereto, and that cutting off of the injector is accomplished by moving the handle or lever in the opposite direction throughout its entire range of movement. It is also obvious that I have provided an injector in which the heat and velocity of exhaust steam when such steam is available are conserved and made to do useful work in the injector and which correspondingly enhance the boiler efficiency of the locomotive. It is also apparent that no attention whatsoever need be paid to the exhaust steam. When present, it automatically enters the injector and performs its function. When not present, the exhaust steam valve automatically remains closed, and when the injector is cut off, the exhaust steam valve is automatically locked closed, so that if exhaust steam should be present at the locomotive side of the valve 66, it cannot enter the injector.

While I have in the above description disclosed what I believe to be a preferred and practical embodiment of my invention, characterized by relatively few parts and simplicity in design, construction and assemblage, it will be understood to those skilled in the art that the details of construction and the arrangement of parts are largely by way of illustration and not to be construed as limiting the scope of the invention which is defined in the appended claims.

What I claim as my invention is:

1. Steam injector with variable water volume delivery comprising a venturi, a water supply conduit leading thereto, a steam supply conduit communicating therewith divided into a forcing nozzle and an entraining nozzle, the latter being positioned in water-entraining relation to said water supply conduit, valves in said steam supply conduit and in said water supply conduit movable together at proportionate speeds, said valves each having a closed position, a full capacity open position, and a range of further movement beyond the full capacity open position, said water supply conduit having a bore constriction, and cooperating structure of the water supply conduit valve forming with said bore constriction throttling means for said water supply conduit, said cooperating structure having a normal range of throttling movement substantially limited to that phase of the movement of said valves which takes place beyond their full capacity open position.

2. Steam injector with variable water volume delivery comprising a venturi, a water supply conduit leading thereto, a steam supply conduit communicating therewith divided into a forcing nozzle and an entraining nozzle, the latter being

positioned in water-entraining relation to said water supply conduit, valves in said steam supply conduit and in said water supply conduit movable together at proportionate speeds, said valves each having a closed position, a full capacity open position, and a range of further movement beyond the full capacity open position, said water supply conduit having a bore constriction, and cooperating structure of the water supply conduit valve forming with said bore constriction throttling means for said water supply conduit, said cooperating structure having a normal range of throttling movement substantially limited to that phase of the movement of said valves which takes place beyond their full capacity open position, said constriction being located between the throttle forming structure of said water supply conduit valve when said valve is closed, and the full capacity open position of said valve so as to be passed momentarily by said throttle forming structure in the movement of said valve from closed to full capacity open position, the capacity of said water supply conduit between said water supply conduit valve and said entraining nozzle being sufficient to continue to supply the injector during the momentary passage of said valve structure past said constriction, whereby the momentary throttling effect of said passage is nullified.

3. Steam injector as claimed in claim 2, the said cooperating structure comprising a disk secured in spaced relation to the water supply conduit valve.

4. In a steam injector, a venturi having a forcing nozzle and an entraining nozzle both communicating with a live steam supply, and means providing a water supply conduit communicating with said venturi at the mouth of said entraining nozzle, a live steam valve and a water valve respectively controlling the supply of live steam and water to said venturi, said live steam valve comprising a member controlling the admission of steam to the forcing nozzle, a lever connecting said forcing nozzle controlling member and said water valve for effecting their simultaneous operation at proportionate speeds, the water valve opening at a faster rate, said valves reaching their full capacity open position early in their respective ranges of opening movement, said live steam valve also including a member controlling the admission of steam to the entraining nozzle, actuated by said forcing nozzle controlling member after some lost motion between said members at the beginning of the valve opening movement of said lever, and means for adjustably varying the lost motion between said members to vary the synchronization of the opening of said live steam and water valves, said water supply conduit having a bore constriction, and cooperating structure of the water supply conduit valve forming with said bore constriction throttling means for said water supply conduit, said cooperating structure having a normal range of throttling movement substantially limited to that phase of the movement of said valves which takes place beyond their full capacity open position.

5. In a steam injector, a venturi having a live steam supplied forcing nozzle and a live steam supplied water-entraining nozzle, means forming a water conduit communicating with a water supply and with said venturi at the mouth of said water-entraining nozzle, an exhaust steam nozzle communicating with a source where exhaust steam may or may not be present discharging

into said water conduit dependently upon the presence of exhaust steam at said source, a live steam valve and a water valve respectively controlling the admission of live steam to said forcing and entraining nozzles and the admission of water to said conduit, means for manually operating said valves, and a valve controlling the admission of exhaust steam to said exhaust steam nozzle automatically actuated through pressure of the exhaust steam at said source.

6. In a steam injector, a venturi having a live steam supplied forcing nozzle and a live steam supplied water-entraining nozzle, means forming a water conduit communicating with said venturi at the mouth of said water-entraining nozzle, an exhaust steam nozzle discharging into said water conduit, a live steam valve and a water valve respectively controlling the admission of live steam to said forcing and entraining nozzles, and the admission of water to said conduit, a lever for simultaneously operating said valves, to which said valves are commonly connected at different distances from the fulcrum of said lever for moving said valves at proportionate speeds, the water valve moving at the faster rate, a valve controlling the admission of exhaust steam to said exhaust steam nozzle, and operating means therefor comprising a cylinder, a stem for said valve passing through said cylinder, a plunger on said stem within said cylinder actuated by exhaust steam pressure for opening said exhaust steam valve, said lever overlying said valve stem in locking relation thereto when all three valves are in closed position.

7. In a steam injector a main venturi having a forcing nozzle and a water entraining nozzle, means forming a water conduit communicating with a water supply and with said main venturi at the mouth of said water entraining nozzle, a part of said water conduit being an auxiliary venturi with its pressure end toward said main venturi, an exhaust steam nozzle extending into said water conduit into entraining relation to said auxiliary venturi and communicating with a source where exhaust steam may be present, a normally closed exhaust valve controlling said exhaust steam nozzle, opened by exhaust steam pressure from said source, and valves operable independently of said exhaust steam valve, controlling respectively the admission of live steam to said main venturi and water to said water conduit, whereby said auxiliary venturi functions alternatively, in the absence of exhaust steam as a mere conduit supplying said main venturi, and in the presence of exhaust steam to deliver additional water, heated and with pressure, to said main venturi.

8. In a steam injector, a venturi having a live steam supply and a conduit from a water supply communicating therewith, correlated live steam and water valves controlling respectively the supply of live steam and water to said venturi, said conduit including a preheater for the water supplied to said venturi, in communication with a source at which exhaust steam may or may not be present, and activated dependently upon the presence of exhaust steam, and a normally closed valve controlling the admission of exhaust steam to said heater, automatically opened by pressure of exhaust steam from said source.

9. In a steam injector, a venturi having a live steam supply and a conduit from a water supply communicating therewith, correlated live steam and water valves controlling respectively the supply of live steam and water to said venturi, said

conduit including a preheater for the water supplied to said venturi, in communication with a source at which exhaust steam may or may not be present, and activated dependently upon the presence of exhaust steam, and a normally closed valve controlling the admission of exhaust steam to said heater, automatically opened by pressure

of exhaust steam from said source and means correlated with said live steam and water valves for positively holding said exhaust steam valve closed when said live steam and water valves are closed.

WALTER H. TINKER.
